UNITED STATES PATENT OFFICE.

CHARLES A. KOEHLER, OF DECATUR, ILLINOIS.

VAPOR-BURNER.

SPECIFICATION forming part of Letters Patent No. 270,191, dated January 2, 1883.

Application filed April 10, 1882. (No model.)

To all whom it may concern:

Be it known that I, CHARLES A. KOEHLER, a citizen of Bavaria, Germany, residing at Decatur, in the county of Macon and State of Illinois, have invented a new and useful Improvement in Vapor-Burners, of which the following is a specification.

My invention relates to a new and useful improvement in vapor-burners, the object of which is to provide a device by which the heavier grades of hydrocarbon oils can be successfully vaporized and burned, and thus enable them to be used for cooking and heating purposes, and to do this in such a manner as to avoid the production of smoke and smell, and at the same time produce an intense heat with a comparatively small consumption of oil. I attain these objects by the device illustrated in the accompanying drawing, in which—

Figure 1 represents the entire construction by a transverse vertical section, the several parts being indicated by letters of reference.

A represents the lower or combustion chamber, having a heavy base, H, provided with a central tube, G, and is provided with two endless rows of small perforations, e e, one row being on a line with the bottom of the chamber and one on a line with the under side of the upper division-wall, b. The combustion-chamber A is conical in form, and has a corresponding conical exterior, as shown. Surmounting this conical chamber A, and formed of one and the same casting, is a generating-chamber of somewhat smaller dimensions, having perpendicular sides and an oval top.

At the left in the drawing is a continuation of the base H, which forms a round stem, E, which is tapped out to secure the end of the supply-pipe E'. At this point is a projection running parallel with and forming a part of the inclined side wall of the chamber A, within which a channel, B, is formed, leading to the generating-chamber A', and through which the fluid or oil flows to the generating-chamber from the supply-pipes E'.

C represents the screw-jet valve, having a perpendicular stem, C', provided with a channel, C''. This stem passes up through a hole in the base H, and its upper end is screwed into the division-wall b, as shown. A small shoulder, c', is formed on the outside of the stem C', which,

when the stem is screwed into the division-wall b, fits tightly against the bottom of the base H, and prevents the admission of air. The horizontal portion, or that which embraces the jet c and screw D, is similar to others now in use, as are also the drip-cup F and the manner of connecting it.

The details having been described, the great advantages gained by this improvement are these: The oil or fluid being conducted to the burner in the usual manner through pipes leading from a reservoir, when it reaches the point or part indicated by letter E its course changes and it is conducted in a new and novel manner to the burning jet c. After the burner is once heated in the usual manner, by burning oil or fluid in the drip-cup below, the oil or fluid is quickly generated into gas by the action of the flame on each of the three parts—viz., the tubes and upper chamber.

It will be obvious that the generating-power of the burner is exceedingly strong. The flame, rising from the jet c, passes up through the tube G into the combustion-chamber A, and has no means of escape except through the two rows of small perforations e e, so then the flame, being confined within the chamber A for a time, heats the whole frame of the burner and produces the first generation of the oil or fluid into gas in the channel B. From thence it rises and fills the generating-chamber A', within which its temperature is raised. By the more direct action of the flame upon the entire outer surface of this chamber, which it completely envelops, the gas or vapor therein passes down through this tube and it is superheated and expanded to its fullest capacity, by which means a greater force is imparted to the flame and the intensity of heat materially increased, thus rendering it practicable to use any of the heavier hydrocarbon oils.

In casting this burner a sand core is placed in mold to form the chamber A, and is removed through the tube G. The upper chamber is also formed with a sand core, which is removed through an opening at the top, which is afterward plugged up by a screw, a, as shown. All of the other holes and channels are drilled.

I am aware that vapor-burners have been constructed in which the fluid is conducted in a tube passing through two concentric rings

of flame, the fluid becoming vaporized during its passage through said tube, and also that in a burner using a wick and having a vaporizing chamber the vapor has been conducted 5 to the burning-point through the hottest part of the flame. I therefore do not claim such construction, broadly, my invention consisting in means for utilizing the heavier hydrocarbon oils by providing more efficient vaporizing apparatus and a superheating pressure-chamber of sufficient capacity to maintain a constant supply of heated vapor.

What I claim, and desire to secure by Letters Patent, is—

In a vapor-burner for heavy oils, the combination of the dome-shaped mixing-chamber A, provided with the inclined vapor-supply tube B, terminating in the superposed vapor-heating pressure-chamber A', with the vapor-conducting tube C', extending downward from chamber A' through chamber A, and provided with jet-orifice, drip-cup, and regulating-valve, as shown and described.

CHAS. A. KOEHLER.
